DESIGN FOR A DOLL CART

Elmer Szantay, Chicago, Ill., assignor to Sandee Manufacturing Company

Application March 6, 1948, Serial No. 144,956

Term of patent 14 years

(Cl. D34—15)

To all whom it may concern:

Be it known that I, Elmer Szantay, a citizen of the United States, residing at Chicago, county of Cook and State of Illinois, have invented a new, original, and ornamental Design for Doll Cart, of which the following is a specification, reference being had to the accompanying drawing forming a part thereof, in which—

Fig. 1 is a top plan view of the doll cart showing my new design;

Fig. 2 is a side elevational view thereof;
Fig. 3 is a front elevational view thereof, and
Fig. 4 is a rear elevational view thereof.

I claim:

The ornamental design for a doll cart, as shown.

ELMER SZANTAY.
